PNEUMATIC WATER SUPPLY SYSTEM

Filed July 19, 1928

Inventor:
Edward F. McCarthy
by Charles O. Hervey
his Atty.

UNITED STATES PATENT OFFICE

EDWARD F. McCARTHY, OF CHICAGO, ILLINOIS, ASSIGNOR TO CHICAGO PUMP COMPANY, OF CHICAGO, ILLINOIS, A CORPORATION OF ILLINOIS

PNEUMATIC WATER-SUPPLY SYSTEM

Application filed July 19, 1928. Serial No. 293,806.

This invention relates to pneumatic water supply systems, and its principal object is to provide a simple and highly efficient apparatus for supplying water to the upper 5 floors of buildings whenever the city pressure falls below that required for furnishing water at these places. Another object is to provide apparatus for constantly supplying water to all floors in the building 10 regardless of the city pressure. Another object is to provide a pneumatic water supply system wherein the pressure is obtained with the use of a fluid displacement pump employing a liquid piston transferable from 15 one tank into another and operating thereby to compress the air.

With these and other objects and advantages in view, this invention consists in a pneumatic water supply system having a reservoir 20 for storing water under pressure and a fluid displacement pump employing a liquid piston transferable from one tank or receptacle into another, and thereby compressing the air in the system.

It further consists in a system as above set forth in which the liquid piston used creates pressure on the water which enters into the reservoir. It further consists in a system as above described which is entirely 30 automatic in operation. It further consists in the several novel features hereinafter fully set forth and claimed.

The invention is clearly illustrated in the drawing accompanying this specification, in 35 which the figure is a diagrammatic view, partly in side elevation and partly in vertical longitudinal section, illustrating a simple embodiment of the invention.

Referring to said drawing, the reference 40 character 2 designates the water supply pipe, which forms a continuation of the city service water pipe, and 3 designates a fragment of the water delivery pipe of the building, which pipe leads to the several floors thereof 45 and has branches on which are the faucets and other outlets, as is well understood. The water supply pipe 2 discharges into the tank 4 of a fluid displacement pump 5.

As shown in the drawing accompanying 50 this specification, the fluid displacement

pump has an upper tank 6 and the lower tank 4, above referred to, and a centrifugal or other water pump 7 for transferring the liquid from the lower tank into the upper one at intervals. The inlet side of the water 55 pump 7 is connected to the lower tank 4 by an inlet conduit 8 and the discharge side of the pump is connected to the upper tank 6 by a discharge conduit 8^a. The water pump is driven by a suitable motor, here 60 shown in the form of an electric motor 9, which is controlled from a pressure switch, as will be hereinafter fully set forth.

Leading from the lower tank 4 to the upper end of the upper tank 6 is an air conduit 10 having an outwardly opening check valve 11 thereon. It will be observed that as the liquid in the lower tank 4 rises therein, the air will be discharged from the lower tank 4 through the pipe 10 and into the upper tank 6. An inlet having an inwardly opening check valve 12 in the lower tank permits atmospheric air to enter the lower tank whenever the level of the liquid therein falls. A valve controlled port or other 70 passageway 13 connects the two tanks 4 and 6 and permits liquid in the upper tank to flow into the lower tank whenever the valve for said port is opened.

The valve 14 which controls the port 13 80 is operated by float mechanism comprising a float 15 contained in the lower tank 4 and operating a float rod 16, here shown as connected to the valve 14 by a lever 17 fulcrumed upon a suitable support in the upper tank. Where the float rod extends through the wall between the two tanks 4 and 6, a stuffing box 18 is provided around the rod to prevent leakage between the two tanks. A lost motion connection is provided between the float 15 and float rod 16, so that the valve 14 may remain open or closed until the float approaches its limits of movement, and, as here shown, shoulders 19 and 20 are provided on the float 85 rod above and below the float and adapted to be engaged thereby, and the float is shown as formed with a central passage 90 through which the float rod extends.

Inasmuch as it is preferable to use a port 100

13 of relatively small diameter, it is advisable to close the discharge conduit 8^a from the water pump while the port 13 is open and, for this reason, a valve 21 may be provided at the discharge end of the conduit 8^a for controlling the passage through said discharge end, said valve 21 being connected to an arm 22 of the float operated lever 17 by a link 23. When the valve 14 is closed, the valve 21 remains open, thereby permitting the water pump to transfer liquid from the tank 4 into the tank 6, but whenever the valve 14 is opened to permit the liquid in the upper tank 6 to discharge 15 into the lower tank 4, then the valve 21 is closed, thereby preventing the pump from discharging any more liquid into the upper tank until substantially all of the liquid in the upper tank has been discharged into 20 the lower one.

Leading from the fluid displacement pump 4 is a combined air and water conduit 24 through which air and liquid may be discharged from the fluid displacement 25 pump and into a reservoir 25 associated with said fluid displacement pump and adapted to store water, or other liquid, under pressure. A check valve 24^a on the conduit 24 controls the passage therethrough. The 30 water delivery pipe 3, heretofore referred to, leads from the lower end of the reservoir 25 and conducts the water from the reservoir to the branch pipes and faucets or other outlets.

35 Under normal conditions of the city water pressure, water enters the lower tank 4 through the discharge end of the water supply pipe 2 and rises therein filling the lower tank 4 and thereafter filling the upper tank 40 6 from which it flows through the conduit 24 and into the reservoir 25. So long as the city pressure remains high enough, water will be available at any of the faucets or other outlets connected to the delivery 45 pipe 3, but when the city pressure falls below normal, then water will not be forced high enough to be available at the upper floors, and under such circumstances, the present system becomes operative for furnishing the pressure necessary to force the 50 water up to the higher floors.

In order to facilitate the operation of the fluid displacement pump, a valve 26 is provided in the water supply pipe 2, which 55 valve is controlled by float mechanism contained in the reservoir 25. In the form of the invention shown, a float 27 is provided upon a float rod 28, which float rod is fulcrumed at a place adjacent the valve 26 and 60 is connected to the lever 29 of the valve 26 by a link 30. The arrangement of the valve and float mechanism, just described, is such that when the float 27 reaches its lower limit of movement, the valve 26 is open, and when the float reaches its upper limit of

movement, the valve 26 is closed. The purpose of the float valve mechanism, just described, is to shut off the supply of water whenever the water in the reservoir 25 reaches a predetermined high level, thereby 70 permitting the fluid displacement pump to act as a pressure pump for creating the necessary pressure in the reservoir 25 to deliver water at any of the higher floors.

If desired, an air vent 31 may be provided 75 in the reservoir 25, which air vent is controlled by a valve 32 connected to the float rod 28 by a valve stem 33 having a lost motion connection with said float rod. The purpose of the air vent is to permit the 80 pressure in the reservoir 25 to be lowered in case the water therein falls to an abnormally low level and in case the pressure in the tank 25 remains above that required to start the pump motor.

For automatically controlling the operation of the water pump, a pressure switch 34 is connected to the reservoir 25 and is interposed in the electric circuit for the pump motor, the wiring of said circuit 90 being indicated at 35. The pressure switch 34 shown is of the ordinary conventional form and is set to open the switch for the circuit when the pressure in the reservoir reaches a predetermined amount, and thereby stop the pump motor, and to close the switch for the circuit when the pressure in the reservoir falls to a predetermined low point, whereby sufficient pressure is always maintained in the reservoir (irrespective of variations of pressure in the city main) to 100 thereby raise the column of water in the pipe 3 to the several faucets or other outlets located at the highest places in the building.

In the operation of the apparatus, and with the parts occupying the positions indicated in the drawing, water flows through the water supply pipe 2 and into the lower tank 4, and assuming that the pressure in the tank 25 is below normal, the circuit to the motor is therefore closed by the pressure switch and the motor 9 and pump 7 are in operation. Water is therefore being transferred from the lower tank 4 into the upper tank 6 by a water pump 7, and if the water is being discharged from the lower tank 4 as fast as it enters the same from the supply pipe 2, the upper tank becomes filled and the water discharges through the pipe 24 into the reservoir 25.

As the level of the water in the reservoir 25 rises, the float 27 is moved upward and finally closes the valve 26, thereby shutting off the water supply pipe 2. The water pump continues to transfer water from the lower tank into the upper one until the float 15 reaches its lower limit of movement, whereupon it opens the valve 14 and closes the valve 21, thereby permitting water contained in the upper tank 6 to flow through 125 130

the port 14 and return to the tank 4. As the water discharges from the upper tank into the lower tank, air contained in the lower tank is forced up through the air conduit 10 into the upper end of the upper tank 6, thereby filling the space formerly occupied by the body of water therein.

When the level of the water in the lower tank 4 reaches an upper limit (thereby raising the float 15 to its upper limit), the float closes the valve 14 and opens the valve 21, whereupon the water pump again operates to transfer water from the lower tank 4 into the upper one, and as the level of the water in the lower tank falls, it creates a partial vacuum therein whereby atmospheric air enters through the air inlet and check valve 12. As the level of the water in the upper tank rises, the air contained in said upper tank 6 is discharged through the conduit 24 into the reservoir 25.

The water contained in the tanks 4 and 6 is transferred intermittently, as above described, until sufficient pressure is built up in the reservoir to operate the pressure switch 34 and thereby break the circuit to the pump motor. The pressure in the reservoir being sufficient, water is available at any of the faucets or other outlets at any of the floors of the building, and when enough water has been drawn out of the reservoir 25 to lower the float 27 sufficiently, the valve 26 is again opened and water is admitted to the apparatus. At this time if the pressure in the reservoir 25 has reached a predetermined low level, the pump will be started again, and if not, the city pressure is sufficient to replenish the water withdrawn from the reservoir and supply water at the faucets or other outlets in the several floors of the building.

More or less variation of the exact details of construction is possible without departing from the spirit of this invention. I desire, therefore, not to limit myself to the exact form of the construction shown and described, but intend, in the following claims, to point out all of the invention disclosed herein.

50 I claim as new, and desire to secure by Letters Patent:

55 1. In a pneumatic water supply system, the combination with a fluid displacement pump employing tanks for receiving water and air, a liquid piston transferable from one tank to another and operating to displace air contained in the tanks and a water pump for transferring the liquid from one tank to the other, said fluid displacement pump being connected to a water supply pipe and having a valve controlled air inlet, of a reservoir into which said fluid displacement pump discharges water and air under pressure, said reservoir being connected to a water delivery pipe.

2. In a pneumatic water supply system, the combination with a fluid displacement pump embodying a liquid piston transferable from one tank to another and operating to displace air contained in the tanks, and an electric motor driven centrifugal pump for transferring the liquid from one tank to the other, said fluid displacement pump being connected to a source of water supply and having a valve controlled air inlet, of a reservoir into which said fluid displacement pump discharges water and air under pressure, said reservoir being connected to a water delivery pipe, and a pressure switch for the electric motor of the centrifugal pump responsive to the variations of pressure in the reservoir.

3. In a pneumatic water supply system, the combination with a fluid displacement pump employing tanks, a liquid piston transferable from one tank to another and operating to displace air contained in the tanks and a water pump for transferring the liquid from one tank to the other, said fluid displacement pump being connected to a water supply pipe, of a reservoir into which said fluid displacement pump discharges water and air under pressure, said reservoir being connected to a water delivery pipe, automatic means responsive to variations of pressure in the reservoir for starting and stopping the water pump, and a float controlled valve on said water supply pipe having its float contained in the reservoir.

4. In a pneumatic water supply system, the combination of a fluid displacement pump employing upper and lower tanks, a liquid piston transferable from one tank to another and operating to displace air therein, a water pump having its inlet end connected to the lower tank and its discharge end to the upper tank, a float controlled water port between said tanks and a check valve controlled air conduit between said tanks, said fluid displacement pump being connected to a water supply pipe and having a check valve controlled air and water discharge conduit, and a reservoir into which said air and water discharge conduit opens, said reservoir having a water delivery pipe leading therefrom.

5. In a pneumatic water supply system, the combination of a fluid displacement pump employing upper and lower tanks, a liquid piston transferable from one tank to another and operating to displace air therein, an electric motor driven centrifugal water pump having its inlet end connected to the lower tank and its discharge end connected to the upper tank, a float controlled water port between said tanks, and a check valve controlled air conduit between said tanks, said fluid displacement pump being connected to a water supply pipe and hav-

ing a check valve controlled air and water discharge conduit, a reservoir into which said air and water discharge conduit opens, said reservoir having a water delivery pipe leading therefrom, and automatic means for starting and stopping the electric motor of the pump, said automatic means being responsive to variations of pressure in the reservoir.

10 6. In a pneumatic water supply system, the combination of a fluid displacement pump employing upper and lower tanks, a liquid piston transferable from one tank to another and operating to displace air 70
15 therein, an electric motor driven centrifugal water pump having its inlet end connected to the lower tank and its discharge end connected to the upper tank, a float controlled water port between said tanks, and 75
20 a check valve controlled air conduit between said tanks, said fluid displacement pump being connected to a water supply pipe and having a check valve controlled air and water discharge conduit, a reservoir into 80
25 which said air and water discharge conduit opens, said reservoir having a water delivery pipe leading therefrom, and a pressure switch for starting and stopping the electric motor of the pump, said pressure switch 85
30 being connected to the reservoir and responsive to variations of pressure therein. 90

7. In a pneumatic water supply system, the combination of a fluid displacement pump employing upper and lower tanks, 100
35 a liquid piston transferable from one tank to another and operating to displace air therein, a water pump having its inlet end connected to the lower tank and its discharge end to the upper tank, a float controlled water port between said tanks and the 105
40 check valve controlled air conduit between said tanks, said fluid displacement pump being connected to a water supply pipe and having a check valve controlled air and
45 water discharge conduit, a reservoir into which said discharge conduit opens, said reservoir having a water delivery pipe leading therefrom, and a float controlled valve on 110
50 said water supply pipe, the float of said valve being located in the reservoir. 115

8. In a pneumatic water supply system, the combination with a fluid displacement pump employing tanks, a liquid piston transferable from one tank to the other and 120
55 operating to displace air contained in the tanks, a water pump for transferring the liquid from one tank to the other, and a water supply pipe discharging into said fluid displacement pump, of a reservoir in- 125
60 to which said fluid displacement pump discharges water and air under pressure, said reservoir being connected to a water delivery pipe, and a float controlled air vent for said reservoir.

65 9. In a pneumatic liquid supply system,

the combination with a fluid displacement pump employing tanks, a liquid piston transferable from one tank to another and operating to displace compressible fluid contained in the tanks, and a pump for transferring the liquid from one tank to the other, said fluid displacement pump being connected to a liquid supply pipe and having a valve controlled compressible fluid inlet pipe, of a reservoir into which said fluid displacement pump discharges liquid and compressible fluid under pressure, said reservoir being connected to a liquid delivery pipe. 75
